UNITED STATES PATENT OFFICE

DODSON HASLUP, OF GRAFTON, WEST VIRGINIA

DISPLAY CABINET

Application filed January 19, 1928. Serial No. 247,940.

This invention relates to display cabinets and especially to the display of articles such as stockings, socks and the like which are formed of fabric and must therefore be ⁵ fully supported in display position.

An object of the invention resides in the construction of such a display cabinet which, although of relatively small dimensions, is capable of neatly supporting in ¹⁰ display position a large number of articles.

Another object of the invention consists in so designing a cabinet as to permit of the ready insertion and removal of articles without disturbing other articles displayed ¹⁵ adjacent thereto.

Other objects and advantages of the invention will be apparent from the following description when taken in connection with the accompanying drawing; in which

²⁰ Figure 1 is a front elevation of the improved display cabinet.

Figure 2 is a vertical section through the cabinet, parts being broken away to more clearly show the construction; and

²⁵ Figure 3 is a fragmentary transverse section taken on line 3—3 of Figure 1.

Referring to the drawings more specifically, the numeral 1 designates the display cabinet generally, and this cabinet includes a ³⁰ bottom wall 2, back wall 3, sides 4, top 5, and a front 6 provided with a transparent display panel 7 of glass or similar material. The front wall 6 is hinged at its bottom edge as indicated by numeral 8 and is provided ³⁵ with latches 9 by which the same may be secured in closed position. The rear wall 3 is also hinged at its lower edge as indicated by the numeral 10 and is provided with a latch 11 for locking it in closed position.

⁴⁰ Either or both the front and back wall may be provided with knobs 12 by which these members may be manipulated.

As already stated the particular object of the present invention is for the purpose ⁴⁵ of displaying in a neat, attractive and com-

pact manner a plurality of flexible articles such as men's and ladies' hose. To this end there is mounted within the cabinet in the present embodiment of the invention four bars 13 which are provided with pairs of ⁵⁰ perforations 14 and 15; each pair of perforations consisting of a perforation 15 adjacent the front of the cabinet and a perforation 14 higher up in the rear row of perforations 14. These bars 13 are arranged in ⁵⁵ pairs as more clearly indicated in Figure 3 and the perforations 14 and 15 thereof are adapted to receive the supporting pins 16 and 17 which are arranged in two series and preferably in staggered relation as indicated in the vertical sectional view shown in ⁶⁰ Figure 2.

As also indicated in Figure 2 it will be seen that the hose is doubled over a pair of the pins 16—17 so as to display only that ⁶⁵ portion of the hose which extends over the pins. It will be obvious that the number of pairs of hose displayed in a cabinet of a given size may be varied according to the spacing of the pins 16—17 vertically of the ⁷⁰ bars 13, depending upon the amount of the fabric of the hose which it is desired to display. In the present instance the cabinet is designed to display forty-eight pairs of ⁷⁵ hose, where the portion displayed is reduced to a minimum.

The bars 13 are secured at the top and bottom of the cabinet and have mounted on the forward edges thereof label holders ⁸⁰ 18 of metal or the like, and adapted to receive labels bearing any desired indicia. Also mounted within the cabinet are a plurality of locking bars 19, these being three in number in the present instance. These bars serve to lock the pins 16 and 17 within ⁸⁵ the apertures 14 and 15 by reason of their proximity to the ends of the pins thereby limiting the longitudinal movement of the pins with respect to the apertured bars 13 in which they are mounted. The bars 19 ⁹⁰

may be mounted in various ways in the cabinet, it only being necessary that they be readily movable to clear the ends of the pins 16 and 17 so as to permit the removal of the latter. In the present embodiment 5 of the invention the bars 19 are shown as provided with projections or nibs 20 on their lower ends adapted to seat in recesses 21 formed in the bottom wall 2 of the cabinet. The upper ends of the locking bars 19 may 10 be secured in position behind the display front 6 by means of pivoted latches 22 which engage the upper ends of the bars.

In removing the pair of hose from the 15 cabinet it is preferred to also remove the pair of pins on which the hose is supported. For this purpose it is only necessary that the bar 19 adjacent either of the ends of the pins be moved to a position out of alignment with the pins thereby permitting the latter to be moved longitudinally in either direction until the respective ends of the pins clear the apertures 14—15. The pins may then be moved in the opposite direction until they entirely clear the bars 13 at which time both the pins and the hose mounted thereon may be removed from the cabinet. Also in placing a pair of hose within the cabinet they are first doubled over a 20 pair of the pins and the pins inserted in the apertures of the bars 13 in a manner similar to that just described.

To facilitate the insertion of the hose in and their removal from the cabinet, it is 25 desirable to segregate the particular pair of hose from the other hose in the cabinet and particularly from the hose adjacent to the position of the hose being inserted or removed, so as to prevent the disarrangement 30 of the adjacent hose by contact therewith. For this purpose I preferably employ two cardboard plates 23 as shown in Fig. 2. In removing the hose from the cabinet the rear door 3 being open, the cardboard plates 45 are inserted at opposite sides of the hose to be removed thereby completely segregating the particular pair of hose from the adjacent pairs. The latch 22 is then moved so as to release the upper end of the pin 50 locking bar 19 and the latter moved out of the way so as to permit the particular pair of pins 16 and 17 to be moved in the manner heretofore described, so as to release them from the supporting bars 13. The hose 55 may then be readily removed from the cabinet and as already stated, a pair of hose may be placed in the cabinet in substantially the same manner. It will thus be apparent that the hose may be readily removed or 60 placed within the cabinet without in any way disturbing the hose displayed adjacent thereto.

From the foregoing description taken in connection with the accompanying drawings it will be observed that I have devised 65

an extremely neat and compact construction by which a large number of hose may be attractively displayed in a small space without unduly restricting their handling for sales purposes. Furthermore, it will be apparent that I have devised an extremely novel arrangement by which portions of many pairs of hose may be displayed in substantially the same plane, thereby facilitating comparison of designs, colors, quality, 70 75 etc.

In accordance with the patent statutes I have described what I now believe to be the best embodiment of the invention, but I do not wish to be understood thereby as limiting myself or the scope of the invention, as many changes and modifications may be made without departing from the spirit of the invention; all such I aim to include in the scope of the appended claims. 80 85

What I claim as new and desire to secure by Letters Patent is:

1. A display cabinet including a receptacle, a transparent front for said receptacle, a plurality of perforated bars disposed behind said front and connected to said cabinet, pins arranged in pairs and having their ends mounted in said perforations, and locking bars in said cabinet to prevent endwise displacement of said pins. 90 95

2. A display cabinet including a receptacle, a transparent front for said receptacle, a plurality of apertured bars disposed behind said front and connected to said cabinet, pins arranged in pairs and having their ends mounted in the apertures of said bars, locking bars in said receptacle for preventing endwise displacement of said pins, and means for removably supporting said locking bars so as to permit removal of said 100 105 pins.

3. A display cabinet including a receptacle, a transparent front for said receptacle, a plurality of apertured bars disposed behind said front and connected to said cabinet, pins arranged in pairs and having their ends mounted in the apertures of said bars, locking bars in said receptacle for preventing endwise displacement of said pins, and means for removably supporting said locking bars, said means including latches for engaging said bars. 110 115

4. A display cabinet including a receptacle, a plurality of apertured bars disposed in said receptacle and connected thereto, pins arranged in pairs and having their ends mounted in the apertures of said bars, upwardly inclined locking bars for said pins, latches for engaging the upper ends of said bars, and means for anchoring the 120 125 lower ends of said bars.

5. A display cabinet including a receptacle, a plurality of apertured bars disposed in said receptacle and connected thereto, pins arranged in pairs and having their 130

ends mounted in the apertures of said bars, upwardly inclined locking bars for said pins, latches for engaging the upper ends of said locking bars, and projections on the 5 lower ends of said locking bars seated in recesses formed in the bottom of the receptacle.

6. In a display cabinet a pair of apertured substantially upright bars and a plurality 10 of pins removably mounted in overlapping pairs in said apertures, whereby a plurality of flexible articles may be doubled over said pins with their display surfaces overlapping.
